UNITED STATES PATENT OFFICE

FRANZ KRUCKENBERG AND FRITZ HEYNER, OF HEIDELBERG, GERMANY; SAID
HEYNER ASSIGNOR TO SAID KRUCKENBERG

RAILWAY SIGNALING SYSTEM

Application filed April 30, 1928, Serial No. 274,089, and in Germany May 5, 1927.

The new signaling system, which is designed for use on a railway operating at high speeds up to 100 metres per second, has the important result of theoretically reducing the space transport sequence, that is, the distance between two succeeding transports to the braking distance and thus permits the time sequence to be reduced to the very lowest possible figure. The basis of the railway signaling systems at present in use is that as long as one transport is within a given section, the so-called block section, the following transport must not enter this section. If the block sections are made equal to the braking distance, the smallest possible space interval between transports for two transports running at full speed is given by a length equal to twice the braking distance plus the necessary safety distance and the greatest train length. If this be compared with the space interval permitted by the invention, the numerical value of the advantage of reducing the space interval to one braking distance, that is to a fraction less than half that necessary with existing signaling systems, will be seen.

Shortly stated the means by which this result is obtained consist in that the necessary braking distance is shown at every instant to the rear of the forwardly proceeding vehicle by a suitable signal system. Accordingly, in the simplest embodiment, behind each individual moving transport is what may be called a moving signal train of the length of a braking section which alters the normal condition of the signal system—the all clear position of the signals—over its whole length. The end of this signal train may be indicated by a "stop" signal, which is always located close behind the leading transport, while the beginning may be marked by a preliminary signal which moves at a predetermined distance behind the stop signal. In normal or uninterrupted traffic the following transport runs close behind the preliminary signal. If, however, the leading transport meets with some difficulty (comes to rest or the like), the following transport will pass the preliminary signal and can no longer observe it. This forms the notice for the driver to brake. If he then brakes properly he brings the trans-

port to rest in good time before the end of the braking section, that is before reaching the halt signal.

The above described theoretically continuous signal train would involve such a large number of signals and controlling devices that the practical carrying out of this system would be impossible. For practical operation, therefore, according to the invention an intermittent or step by step following up by the signal train is provided, that is the braking section is sub-divided by the arrangement of the signaling means. The signal train then follows in steps by the amount of one subdivision of the braking section. Accordingly as the subdivision of the braking section is greater or less so will the progression of the signal train following the transport approach more or less closely to the ideal conditions.

Where high speeds are employed, the braking sections and therewith the signal trains are very long. If now the signal train comprises only a stop signal close behind a leading transport and a preliminary signal which indicates the beginning of the braking section and moves closely before the following transport, there is no possibility of giving the driver any indication of his relative position when he is between the two signals. To avoid this disadvantage, the leading transport is followed by a signal train not only with signals at its beginning and end, but with signals at its subdivision points also. These signals are different from the all clear, preliminary and stop signals so that from their character the driver can judge the distance from the transport in front. With the highest speeds aimed at, the use of point form signals, as for example single lamps, is impossible. They would not act on the perception of the driver for a sufficient time, particularly when atmospheric influences (fog, rain and so forth) introduce difficulties. In the new system therefore not point form, but to a certain extent line form signals such as tubular incandescent lamps, or elongated gaseous conduction lamps are provided. Both the normal signal indication and the signal train comprise a close sequence of individual signals which appear

as a substantially continuous signal to the passing driver.

In the operation of the new system optical signals electrically controlled may be used in various forms. The braking section is divided into several, for example four, subdivisions. The signal train comprises a sequence of coloured lamps, the subdivision immediately behind the leading transport consisting of a sequence of red lamps. The two following subdivisions respectively comprise orange and dark yellow lamps. The fourth subdivision at the commencement of the train comprises yellow signal lamps. Behind this the signal lamps can have the normal indicating colour say green. Advantageously, however, this last subdivision is indicated, for instance, by white preparing or warning lamps which indicate to the driver that the braking section commences with the next subdivision. In this case the addition for reaction time, that is the time elapsing between the perception of the signal to brake and the application of the brakes, to the braking section, can be considerably reduced, which is advantageous in obtaining the lowest time sequence of the transports.

The invention is further described with reference to the accompanying drawings, in which—

Figs. 1 and 2 are circuit diagrams showing a signaling system constructed according to the invention,

Figs. 3 and 4 are circuit diagrams showing portions of the signaling circuit with the switches shown in their positions during certain stages of the operation, and

Figs. 5 and 6 are views of portions of a signaling circuit, showing additional switches which are employed in certain cases.

Referring first to Figure 1 the figure extends over seven times the length of a signal group, or subdivision of a braking section, the subdivisions being lettered in order from *a* to *g*, since each of the subdivisions is similar to every other subdivision, the switch mechanisms in certain of the subdivisions have been omitted and have been indicated merely by a rectangle. At each subdivision point is a set of six differently coloured signal lamp groups here represented by single lamps. 61 is red, 60 orange, 59 dark yellow and 58 yellow, which four groups limit the full braking section. 57 is white and serves as a warning or preparing signal and 56 is green indicating 'all clear.' For the automatic switching of the signal lamps, magnetic switches in conjunction with rail contacts actuated by the transports have been chosen by way of example. The magnetic switches and rail contacts are included in a signal current circuit *S*, the signal lamps in a lamp current circuit *L*. An emergency circuit *N*, as can easily be seen, serves to set the whole signal system at danger. In the normal 'all clear'

condition of the system all the magnetic switches are in the attracted position.

The switching operations can be followed by reference to Figures 1 and 2. If a vehicle *A* is in the position shown for example in Figure 1, that is in front of the rail contact of the subdivision point *g*, the switched in green lamp 56 indicates 'all clear' to the driver, since the armatures belonging to the magnet coils 51—55 are all attracted. When vehicle *A* runs on to the rail contact 50, then as shown in Figure 2 for the subdivision *g*, the circuit containing the field coils 51—55 is short circuited over the contact 50, all the armatures for the subdivision *g* are retracted and the red lamp 61 is switched in over the contact 62 (Figure 2 subdivision *g*); the vehicle *A* is therefore covered. The signal position in subdivisions *h* and the succeeding groups (not shown) remains unchanged. This continues for the further travel of the vehicle *A* until it reaches the next contact (not shown) and again short circuits the corresponding field windings. The armatures are retracted, the green lamp 56 is cut out and the red lamp 61 switched in. The vehicle *A* is now covered on the next subdivisional section by the respective red lamp 61. In the example the signal train which the vehicle *A* so to speak draws after itself, is as long as one braking section, subdivided into four. If the above described clearing of the signals is to be provided, at this point in the subdivisional section *e* (Figure 1) the respective orange lamps 60 must be switched in in place of the red group 61. From Figure 1 it will be seen that this operation in fact takes place. In consequence of the closure of contact 50 (Figure 1 subdivision *g*) a circuit is closed. From +S (Figure 1, *f*) a current can flow over winding 55, switch 63, leads 64 and 65, rail contact 50 back to —S in the subdivisional section *g*. In this way the armature of winding 55 is attracted (as seen in Figure 1 subdivision *e*) and switches in the orange lamp 60 in subdivision *e* through switch 62.

On further travel of the vehicle *A* the same switching operation is repeated. The green group 56 is cut out and the red group 61 switched in. The closing of the next rail contact 50, Fig. 1 closes a further circuit. From +S in section *e*, Fig. 1 a current flows over winding 54, switches 66 and 67, leads 68, 69, 64, 65 and rail contact 50 in section *g* back to —S. The sections *d*, *e*, *b*, and *a* are energized in an analogous manner to switch in lamps 59, 58, 57 and 56 respectively.

When the vehicle *A* has reached the subdivisional section *g* as shown in Figure 1, it is covered by a complete signal train. In the subdivisional sections *f*, *e*, *d*, *c*, respectively the red, orange, dark yellow and yellow lamps 61, 60, 59 and 58 are switched in. In section *g* the normal signal indication exists since the green lamp 56 is switched in. In *b* the white

warning lamp 57 is switched in and in *a* there is again the normal indication by the green lamp 56.

The described switching sequence repeats itself continuously in regular operation.

If for any reason (mishap, stop signal or the like) the vehicle A comes to a standstill in the position shown in Figure 1, a following vehicle (not shown) can still run at full speed to the end of the subdivision *b* (Figure 1) covered by the white warning lamps and in doing so will effect the above described switching operations behind itself. The driver knows that he must brake from the appearance of the yellow lamps at the point *c* in order to bring his vehicle to rest in good time at the end of the subdivision *f* covered by the red lamp. When the subdivision *b* is passed and the respective contact 50 closed the windings of the magnetic switches 51-55 traversed by current are short circuited and their armatures retracted. The white lamp 57 is cut-out over switch 62 and the red lamp switched in. Further behind the above described switching operations take place. In the section *a* the orange lamp 60 is switched in place of the red group 61 and so forth. The switching operations on further travel of the vehicle are also similar to those above described. Finally the second vehicle as shown in Figure 2 will come to rest in the subdivisional section *f* covered by the red lamp 61. The vehicle B itself is also protected by a complete signal train. Further vehicles can collect, see for example vehicle C of Figure 2. The last vehicle is always protected by its signal train.

It is advantageous for the end of the subdivisional section covered by red lamps to be particularly indicated, so that the end of the braking section is definitely shown to the driver. This can be effected for example by a particular configuration of the signal.

In Figure 2 the subdivisional sections *a*-*c* are omitted, but the figure is supplemented by a further section *h*. Three vehicles A, B, C, have moved into the position indicated and the signals in the sections *d*, *e*, *f* have been correspondingly switched. If now the vehicle A can move further, say through receiving the all clear signal, or through a breakdown being repaired, then on passing over the rail contact 50 of the section *g* Figure 2, the corresponding windings 51-55 will be short circuited. The armatures of these windings will accordingly be retracted. The green lamp 56 will be cut out, the red lamp 61 switched in. A current can then flow over switch 63 at *f* Figure 2, from +S (Figure 2 *f*), over winding 55, leads 64 and 65, rail contact 50 back to -S in section *g*. The armature belonging to the winding 55 *f* will be retracted and instead of the red lamp 61 the orange lamp 60 will be switched in as shown in Figure 2.

In contradistinction to the further switching operations with open sections behind the vehicle A there is now no possibility of further current flow over the closed rail contact 50 in section *g* Figure 2. In section *e* the switch 70 with the red lamp 61 switched in, prevents any flow of current and this prevents the switching in of the dark yellow lamp 59 in place of the red lamp 61 switched in owing to the position of the vehicle B. In an analogous manner, lamp 60 of group 60 of group *d* is energized. In this way the switching out of the correctly connected orange lamp 60 is prevented and the yellow 58 is not switched in as would be the case if the sections behind vehicle A were not occupied. On further movement of the vehicle A corresponding switching operations take place until finally the white group 57 appears before the vehicle B, which permits it to proceed. For the case where the vehicles are starting from rest, the driver can naturally be given special instructions, so that he starts say as soon as the dark yellow lamp group appears, so that the time interval between the subsequently starting vehicles may not be too great. The exact time of starting so that a predetermined time sequence of vehicles can be maintained, can easily be determined for particular lines, the highest speed, braking retardation, starting acceleration and other such factors being known.

Interruptions and faults of the most varied kind are met by the invention as follows:

The burning out of individual lamps is harmless since the lamp groups as such remain in existence and maintain their signaling functions. The failure of individual magnetic switches to operate only causes internal interruptions within the particular switch group. Assuming in the course of the switching operation the magnetic switch 52 (Figure 3) by the operation of which the dark yellow lamp 59 should be switched in, remains out. Then, since the switch 71 is not changed over, there is no possibility of the magnetic switches 53, 54 and 55 being actuated. No lamp group therefore can ever be switched in which lies nearer in the signal train to the all clear lamps than the switched-in orange. On the contrary this remains unchanged until the rail contact 50 (Figure 3) is again closed by a vehicle running over it. Then the winding of the switch 51, which is still traversed by current, is short circuited and its armature is retracted, thus switching in the red group 61. This fault is of no effect on the vehicle sequence, since the neighbouring magnetic switch groups form a correct signal train up to the wrongly indicating group independently of the faulty switch. There is simply a slight loss of time, since the driver will be unexpected-

ly obliged to brake for one subdivisional braking section.

With sticking of the armature of one individual magnetic switch no interference with the signal train is caused. It is different when a number of neighbouring switches stick simultaneously. In this way a wrong lamp group is switched in by the respective magnetic switch group, this time of higher order than is correct. In Figure 10 it has been assumed that the armatures of the magnetic switches 51, 52, 53 have stuck simultaneously. In this case if for example the all clear condition previously existed and a vehicle closes the contact 50, instead of the correct red lamp 61, the incorrect yellow lamp 58 would be switched in. The driver would thus be permitted to brake less strongly. This can only be dangerous if the leading vehicle remains stationary behind the faulty magnetic switch group and the driver of the following vehicle has not the presence of mind to apply the emergency brake.

The likelihood of a collision in this case is extremely small since the following vehicle can have but a low speed, and the red tail lights of the leading vehicle will be seen sufficiently early and certainly at such low speed. With the aid of a few additional switch members it is possible to make the further switching of one magnetic switch group dependent on the correct switching of the previous group, so that the increased insistence of the driver's presence of mind can be avoided.

A further interference in signaling can be caused by non-functioning of the rail contacts. There then remains without change a complete signal train behind the non-functioning contact, which unconditionally compels the following vehicle to come to rest. In this case the vehicles must be dispatched over the sections with the faulty signals by special emergency instructions. It is further possible by simple measures (see Figure 5), namely by further switches 74 and 75 to switch out the faulty rail contact and if necessary faulty magnetic switch group until the fault has been remedied. This condition can be indicated to the driver by a separate lamp group which is illuminated simultaneously with the throwing over of the switches 74 and 75. For the greatest security against such interruptions a plurality of parallel connected rail contacts will be used as is shown in the figures described above.

A further possibility of interruption is the breakage of the conductors to the magnetic switches. If such a breakage occurs within the group itself, this group does not act on contact being made and it shows a red light continuously. If for some reason the supply of current from the source ceases, provision can easily be made for a substitute battery to be switched in so quickly that the magnetic

switches which are given a certain inertia do not have time to release before the new supply is switched in. Only breakages of the current conductors cannot be provided for in advance. Present day cable technique, however, makes it possible to install absolutely reliable conductors.

All the lamps are fed, as already mentioned, by a separate lamp feeding circuit (see Figure 6). By this provision all signals are set to "halt" (red light) if the lamp circuit is broken. As can be seen directly from Figure 12, in this case the armature 76 is retracted from magnet 77 and the red lamp group 61 is connected across the emergency circuit $+N-N$. This same emergency circuit can advantageously also be used set the whole line or individual sections to "halt". A single switch 78 in such cases opens the lamp circuit. The armatures 76 of all the magnetic switch groups are retracted and all the red lamp groups are fed by the emergency circuit, without the circuit being changed by further movement of the vehicles. If the lamp circuit is again closed all lamps will be switched in in accordance with the vehicle positions and the operation of the line can immediately recommence in regular manner.

The magnetic switches in the example hereinbefore described, which can be actuated by direct or alternating currents, can naturally be replaced by other switching devices, for example by the known motor relays operating on the rotating field principle. In another form of the invention, the signal operation is effected electrically, while the signals themselves are given in the driver's space within the vehicle, over current collectors and conductor rails.

What we claim is:—

1. In a signaling system for high speed vehicle travel, the combination with means for displaying a substantially continuous band of light extending along the entire path of travel of said vehicle, of means actuated by the progress of said vehicle for controlling said displaying means.

2. The invention as set forth in claim 1, wherein said displaying means comprises an elongated signal member extending longitudinally of the path of travel of said vehicle.

3. The invention as set forth in claim 1, wherein said displaying means comprises an elongated illuminated member.

4. In a signaling system for high speed vehicle travel, the combination with means extending substantially continuously along the entire path of travel of said vehicle for displaying a series of signal indications of different restrictive order with respect to predetermined portions of the path of said vehicle, of means actuated by the progress of said vehicle for displaying said indications successively and in serial order beginning with the most restrictive indication.

5. In a sectionalized signaling system for high speed vehicle travel, the combination with means for displaying bands of light which extend substantially continuously along an entire section of the path of travel of the vehicle, of means actuated by the progress of a vehicle for controlling said displaying means in accordance with the position of said vehicle relative to said section.
- 10 6. In a sectionalized signaling system for high speed vehicle travel, the combination with means for displaying a series of signal indications which extend substantially continuously along an entire section of the path of travel each of said indications being of a different restriction order with respect to predetermined sections of the path, of means actuated by the progress of a vehicle past said section for controlling said displaying means
- 15 20 to display said indications successively and in serial order beginning with the most restrictive indication.

7. The invention as set forth in claim 6, wherein said displaying means comprises a plurality of elongated parallel lamps of different appearance when energized extending along the path of the vehicle.

8. In a signaling system for high speed vehicle travel, the combination with means for displaying signals of different restrictive orders in the form of substantially continuous strips of light each having distinctive coloration extending parallel to the path of travel of the vehicle, of means actuated by the progress of the vehicle for controlling said displaying means to indicate the approximate position of said vehicle.

9. A signaling system for high speed vehicle trains comprising means for displaying a series of signal indications, each of said indications being of a different restrictive order with respect to predetermined portions of the path of said train and control means actuated by the progress of a train past and beyond said portions for displaying said indications successively and in serial order beginning with the most restrictive indication, said control means being divided into a plurality of sections related respectively to each of said portions of said train path and including means for rendering any of said sections inoperative independently of said other sections.

In testimony whereof we affix our signatures.

FRANZ KRUCKENBERG.
FRITZ HEYNER.
